(57) **CLAIM**

The ornamental design for a bicycle frame, as shown and described.

DESCRIPTION

FIG. 1 is a left side view of a bicycle frame, showing my new design in position of use on a bicycle.

FIG. 2 is a right side view of the bicycle frame.

FIG. 3 is a back view of FIG. 2.

FIG. 4 is a front view of FIG. 2.

FIG. 5 is a top view of FIG. 2; and,

FIG. 6 is a bottom view of FIG. 2.

The portions of a bicycle shown in broken lines in FIGS. 1-6 form no part of the claimed design. The broken lines immediately adjacent the shaded areas represent the boundaries of the claimed design and form no part of the claimed design.
